UNITED STATES PATENT OFFICE.

WILLIAM AUGUSTUS KILMER, OF DE KALB, ILLINOIS, ASSIGNOR TO THE AMERICAN STEEL & WIRE COMPANY OF NEW JERSEY, OF HOBOKEN, NEW JERSEY, A CORPORATION OF NEW JERSEY.

SEMIROTARY WIRE-FABRIC MACHINE.

1,195,688.

Specification of Letters Patent. Patented Aug. 22, 1916.

Application filed March 8, 1915. Serial No. 13,022.

To all whom it may concern:

Be it known that I, WILLIAM A. KILMER, a citizen of the United States, and resident of De Kalb, in the county of Dekalb and State of Illinois, have invented certain new and useful Improvements in Semirotary Wire-Fabric Machines, of which the following is a specification.

My invention relates to wire fabric machines and has particular reference to a novel mechanism so constructed and arranged as to more economically produce wire fabric used for fencing and concrete reinforcement.

15 One of the principal objects in the construction of the present device is to eliminate the usual bobbins from which the wires composing the mesh have been taken.

In the present machine the wires composing the mesh may be directed into the machine from the reel. This accomplishes a large saving in time because of the stoppages necessary to renew bobbins in the machines heretofore used.

25 A further object is to provide a mechanism which shall operate more rapidly and which shall require less attention on the part of the operator.

A still further object is to provide a machine which shall be almost entirely automatic in character.

The invention will be more readily understood by reference to the accompanying drawings, wherein,

35 Figure 1 is a front elevation of a machine constructed in accordance with my invention; Fig. 2 is a plan view of the same; Fig. 3 is an end elevation thereof; Fig. 4 is an enlarged detail of the drum carrying the twisters; Fig. 5 is a section on the line 5—5 of Fig. 4; Fig. 6 is a section on the line 6—6 of Fig. 5; Fig. 7 is an end elevation of the drum showing the means for rotating the twisters and maintaining them in proper 40 position at points intermediate the point of rotation. Fig. 8 is a plan view of the primary twisting mechanism and the means for forming the mesh; Fig. 9 is a plan view partly in section showing the twister spindles; Fig. 10 is a section on the line 10—10 of Fig. 8; Fig. 11 is a section on the line 11—11 of Fig. 10, and Fig. 12 is a view of a fragment of the fabric woven by this machine.

Referring more particularly to the drawings it will be seen that I provide frame members 20, within which a shaft 21 is mounted, this shaft having tight and loose pulleys 22. Power for operating the fabric forming mechanism is applied to this shaft. 55 On the shaft 21 is bevel pinion 23, meshing with a bevel gear 24, on a suitable shaft 25, which shaft carries a worm 26, meshing with a worm gear 27, best shown in Figs. 1 and 2. This worm gear is keyed to a shaft 28, 60 upon which the twister drum 29 is mounted. This drum, as best shown in Figs. 4 and 6, may consist in the heads 30, to which the bars 31 are secured by means of screws or bolts 32. These bars may have engaging 65 tongues and screws by which the same are interlocked with each other. These bars when thus assembled on the heads form a rigid structure by means of which a portion of the coiling is accomplished. Mounted between cross bars 33 are the reciprocating bars 34, 35, as best shown in Figs. 5 and 9. A gear 36 engages the two bars and causes their reciprocation in unison but in opposite directions. The coilers consist in a 70 member having an upper squared portion 37 and a lower tubular portion 38, the member being apertured to accommodate a stay wire in case one is desired at that point in the fabric. The coilers are held in place at 75 their upper ends by means of spacers 35'. These spacers are secured at their lower ends to cross bars 33. Located on opposite sides of the bar 37, and held in recesses in the reciprocating bars 34, 35, are segmental 80 twisters 39, 40. These segmental portions are shifted with the bars 34, 35, and serve to form the mesh of the fabric. These bars are likewise apertured to accommodate the wire making up the mesh of the fabric. The 85 shifting of the bars 34, 35 is accomplished by means of the cams 41, 42, which contact rollers 43, carried on the ends of the links or connecting rods 44, which rods are supported by means of the arms 45. Motion is 90 imparted to the cams 41, 42, by the shaft 46, best shown in Fig. 2, on which shaft is mounted the gear 47, actuated by the pinion 48, on the shaft 49. This shaft 49 carries a bevel gear 50, which meshes with a similar 95 gear 51 on the power shaft 21. A particular advantage results in the elimination of the segmental gears by means of which the 100 105

twisters are commonly operated. In my construction it will be noted that the twisters are merely segments, the rotation of the twisters being accomplished by means of the apertured rod 38, best shown in Fig. 11. By reason of this arrangement a single solid pinion may be employed which is secured rigidly to the rod in place of the segmental gears which have commonly been employed in the place of the segments 39, 40, shown in Fig. 9.

The twisting motion is imparted to the segmental twisters by means of the member 37, 38. Gear teeth 52 are formed near the lower end of the tube 38, and with these teeth bars 53, 54 engage as best shown in Figs. 10 and 11. These bars are caused to reciprocate by means of the mechanism best shown in Figs. 8 and 10, which mechanism includes a support 55, within which a cross-head 56 is guided. This cross-head is reciprocated by the pitman 57, which engages the gear 58, best shown in Figs. 1 and 10. This gear is mounted on a vertical shaft 59, and is actuated by a pinion 60, which is rigid on the shaft 49, best shown in Fig. 3. The cross head 56 carries a pair of pawls 61, 62, which pawls engage notches 163 formed in the upper edges of the bars 53, 54. Because of the gear teeth on the tubes 38, the bars are caused to travel in opposite directions. Therefore it will be seen that one thereof is pushed forward in order to secure the return of the opposed bar. The pawls 63 are maintained in and out of engagement with the notches by means of the arms 63, 64, which are actuated through the links 65, 66, connected through a rocker arm 67, the links 65, 66 engaging opposite ends of said arm. This arm is oscillated by a connecting rod 68, movable by a cam 69 mounted on a shaft 70, which shaft as best shown in Fig. 1, carries a bevel gear 71, engaging a similar gear 72, on a short vertical shaft 73. A gear 74 on this shaft is engaged by a pinion 75, mounted on the shaft 59, as shown in Fig. 3. It will be seen from the mechanism thus described that a portion of the coiling is done by the coilers shown in Figs. 5 and 9. This mechanism, however, performs only half of the coiling operation, the remainder of the coiling or twisting being carried out in the drum 29. The bars 31 composing this drum are provided with radial projections which are notched as at 76 in Fig. 6. Extending longitudinally within the bars 31 are worm shafts 77, each of which is provided with a pinion 78 on its overhung end. Also rigid with the shaft is a stop-block 79, as best shown in Figs. 6 and 7. This stop-block acts to maintain the shafts in proper position at different points in the travel of the drum. The squared faces 80 of the stop-blocks engage at certain points in their travel with a fixed cam 81,

this cam being integral with or fixed to a mutilated gear 82, which gear has teeth only at the point of reduction in the cam. This gear 82 engages the pinions 78, and causes rotation thereof at a certain point in the travel of the drum, as best shown in Fig. 7. Also mounted in the bars 31 are twister spindles 83, having gear teeth which engage the worm 77, and are rotated thereby. These spindles are provided with slots 84, 75 within which two wires to be twisted are accommodated. This twisting operation is continuous from the time the gear teeth 82 begin their engagement with the pinion 78, until the gear teeth are discontinued at 85. 80 After leaving the drum the fabric passes between the pull-out rolls 86, 87, after which it is sheared at the proper point and reeled, all of which mechanisms form the subject matter of co-pending application, Serial No. 85 13,023 filed of even date herewith and Letters Patent No. 1,158,505, of November 2, 1915.

The operation of the machine is as follows: The fabric, such as intended to be woven by this machine, is shown in Fig. 12. It will be seen that I may provide longitudinal stay wires 186, these being located as desired in the fabric. The arrangement of the machine is such that stay wires may be 95 located a distance apart equal to the width of one mesh if required. These stay wires are fed into the machine underneath a roller 187, and enter the lower ends of the tubes 38, passing upwardly therethrough, thence 100 through the apertures in the bars 37. From this point the wire enters a notch in the bars 31, such notch being intermediate the notches 76, in which the twisting is accomplished. The wires 88, composing the mesh 105 of the fabric, are also led into the machine under the roller 187, and pass upwardly alongside the tube 38, thence through the apertures in the spindles 39, 40. At this point the mesh of the fence is formed. It 110 will be noted that as the twister spindles which include the parts 37, 39, 40, revolve, the two wires which enter the apertures in the segments 39, 40 are wrapped around the spindle in one direction of rotation of the 115 spindle. The wires are unwound in a subsequent reverse movement of the spindle. By this means the two wires are first wound around the spindle and then unwound in the subsequent actuation thereof. The operation of forming the mesh and twisting the wires at their intersections by means of the mechanism shown in Fig. 9 is well known and need not be further described. After leaving the twisters shown in that figure, the 120 partially woven fabric passes into the drum 29, two wires lying in the notch 84 in the twister wheel 83. The wires then travel at the same speed as that of the drum and as the drum reaches a point immediately fol- 130

lowing the engagement of the wires with the 50
twister wheel the twisting operation is be-
gun, due to the engagement of the gear 82
with the pinion 78. This forms the twist
5 89, shown in Fig. 12, the two wires being
grasped by the twister wheel and being
twisted in opposite directions on each side
of the wheel. The arrangement of the draw-
ings is such that the wheel is given two
10 complete turns, after which the cam 81
causes the blocks 79 to assume the correct
position, whereby the notch 84 in the twister
wheel will register with the notch 76 in the
bar 31. From this point the fabric is pulled
15 out by the rolls 86, 87, and is sheared to
proper length and reeled, all of which last-
named mechanism is described in my co-
pending application and my patent, both
hereinbefore referred to.

20 I claim:

1. In a wire fabric machine, the combi-
nation of wire weaving elements including
a drum, a plurality of twisters mounted on
said drum, a worm shaft for actuating each
25 of said twisters, means for rotating said
drum, and means for actuating said worm
shafts, substantially as described.

2. A wire fabric machine including a
drum, a plurality of twisters mounted in
30 said drum, a worm gear for actuating said
twisters, a worm shaft engaging said worm
gear, means for rotating said drum and for
actuating said worm shaft, substantially as
described.

3. In a wire fabric machine, the combi-
nation of a drum, a plurality of notched
bars mounted on said drum, a plurality of
notched worm gears mounted in said bars,
a worm shaft for actuating said gears, means
40 for rotating said drum, and means for actu-
ating said shaft during rotation of the
drum, substantially as described.

4. In a wire fabric machine, the combi-
nation of a twister spindle, including a flat
45 central portion and a pair of segmental side
portions, each of which portions accommo-
dates a wire, a gear fixed to said central
portion, and rack-bars coöperating with said
gear and adapted to cause the rotation of

said twister spindle, substantially as de- 50
scribed.

5. A twister spindle, including a hollow
rod, a pinion fixed to said rod near its lower
end, the upper end of said rod being squared
segments at each side of said rod at its up 55
per end, and rack-bars engaging said pinion
and adapted to cause rotation of said
spindle, substantially as described.

6. In a wire fabric machine, the combi-
nation of a drum) a plurality of twisters car- 60
ried by said drum, a worm shaft for actu-
ating said twisters, a pinion carried by the
end of said worm shaft, and a stationary
mutilated gear with which said pinion co-
operates during a portion of the rotation 65
of said drum, substantially as described.

7. In a wire fabric machine, the combi-
nation of a drum carrying a plurality of
rows of twisters, a longitudinal shaft for
actuating a row of twisters, a pinion mount- 70
ed on the overhung end of said shaft, a sta-
tionary mutilated gear with which said
pinion coöperates during a portion of a
revolution of said drum, a cam fixed with
relation to said drum, and a cam block car- 75
ried by said longitudinal shaft and adapted
to coöperate with said cam to prevent rota-
tion of said shaft except when said pinion
is in engagement with said mutilated gear,
substantially as described. 80

8. In a wire fabric machine, the combi-
nation of a drum carrying a plurality of
rows of twisters, a single worm shaft for
actuating each row of twisters, a pinion
mounted on the overhung end of said shaft, 85
a fixed gear with which said pinion co-
operates during a part of a revolution of
said drum, and cam means preventing rota-
tion of said shaft during the remainder of
the revolution of said drum, substantially 90
as described.

Signed at De Kalb, Illinois, this 25th day
of February, 1915.

WILLIAM AUGUSTUS KILMER.
